UNITED STATES PATENT OFFICE

ROBERT L. LYONS, OF WALTHAM, MASSACHUSETTS, ASSIGNOR TO AMERICAN BUTTON SEWING MACHINE CO., OF BOSTON, MASSACHUSETTS, A CORPORATION OF MASSACHUSETTS

MACHINE FOR SECURING BUTTONS TO WORK

Application filed March 30, 1929. Serial No. 351,391.

This invention relates to a machine for attaching buttons or the like, more particularly by a sewing operation, wherein stitches are passed through four holes in each button. The invention further relates to certain improvements, certain of which may find utility in connection with other types of sewing machines than those particularly designed for sewing on buttons.

Heretofore it has been usual practice when sewing on four hole buttons by machine, to pass a series of stitches in succession through each of the holes of one pair and then to move the button relative to the sewing instrumentalities to present the other pair of holes to the needle path and then to pass a series of stitches in succession through the holes of this other pair. This shifting of the button relative to the needle during the stitching results in the laying of the thread from one to the other pair of holes over the exposed face of the button, which impairs the appearance of the face or top of the button after it has been attached. Commonly also the holes of each pair through a button are joined by a surface channel in the front face of the button in which the stitches lie, but this cross thread cannot lie in the channel so that not only is it more noticeable but it is exposed over the more prominent surface portion of the button where it is liable to be cut or broken. Moreover, if the stitching is done as commonly with a single thread in chain stitch formation, a breaking of the thread at any point is likely to cause raveling of the thread and the freeing of the button.

The present invention has for one object to provide a mechanism by which four hole buttons may be attached without a cross thread and at a sewing speed for the same speed of the machine at least double that of machines heretofore used. In its preferred form also the machine utilizes a through and through chain stitch, but in such a manner that a break in the thread will not permit the thread to ravel. Further, a more secure anchorage of stitches in the work than heretofore is effected. For securing the greater sewing speed and for the elimination of the cross thread, two needles are employed, one

stitching through one of a pair of holes in the button, and the other stitching through the other of the pair of holes, both needles operating simultaneously so that any given number of attaching stitches are formed in one-half that number of sewing strokes and in a single sewing operation, and for preventing the possibility of raveling and to produce a secure anchorage in the work as well as to simplify the machine, the threads from both needles are taken by a single looper mechanism whereby they become interengaged and locked together back of the button and on the back face of the work. An improved looper mechanism which may find a more general application than to button sewing machines has also been devised, this mechanism being able to operate with threads of a character which cannot be used successfully with the usual loopers heretofore employed.

For a more complete understanding of this invention, reference may be had to the accompanying drawings in which

Figure 1 is a side elevation of the new machine.

Figure 2 is a detail section on line 2—2 of Figure 1.

Figure 3 is an inverted plan of a portion of the machine.

Figure 4 is a view similar to a portion of Figure 3, but showing the looper mechanism in a different position.

Figure 5 is a vertical section through the forward part of the machine on line 5—5 of Figure 2.

Figures 6 and 7 are views similar to portions of Figures 3 and 4, but showing other and successive positions of the looper mechanism during the stitching cycle.

Figures 8, 9, 10 and 11 are detail perspectives showing successive relative positions of the sewing instrumentalities during the stitching cycle.

Figures 12 to 17 are somewhat diagrammatic views showing the manner in which the stitches lie across the button and the work, Figures 12 and 17 showing the button face, Figures 13 and 16 showing the back

of the work, corresponding respectively to Figures 12 and 17.

Figures 18 and 19 are views similar to Figure 4, but showing a modified construction, 5 these figures illustrating two different positions of the looper mechanism.

Figure 20 is a view similar to a portion of Figure 1, but of the modified construction shown in Figures 18 and 19.

10 Figures 21 and 22 are button face and back work face views, respectively, where the button is attached by the mechanism shown in Figures 18 to 20.

15 Figure 23 is a somewhat diagrammatic sectional detail showing the stitch formation effected by this modified mechanism.

20 In Figure 1 a conventional form of sewing machine frame is shown having a work table 1 supporting at its rear end a post 2 having an arm 3 extending forwardly from its upper end and carrying a head 4 to receive the sewing needle mechanism. A needle bar 5 arranged for vertical reciprocation as by any of the usual mechanisms carries 25 on its lower end a needle holder 6 for a pair of needles 7. Positioned on the upper face of the work table is shown a conventional form of button clamp 10 carried on the forward end of an arm 11 pivoted at 12 to a 30 carrier member 13, the rear end of the arm 11 being pressed upwardly as by means of a spring 14 so as to press the button clamp 10 downwardly to clamp the work between its lower face and the cloth plate 76. To the 35 forward end of the carrier member 13 is fixed the cloth plate 76 so that the button clamp and cloth plate move in unison horizontally. The forward end of the arm 11 may have attached thereto a lifting chain of 40 usual form such as 20 which extends to an arm 21 on a rock shaft 22. This rock shaft may be rocked to raise the button clamp to release the work in the usual manner, as, for example, by means of a pull chain 23 45 connected to an arm 24 carried by the rock shaft 22, the chain 23 extending to any suitable actuator such as a treadle in accordance with usual practice. The button clamp and the cloth plate are mounted so as to permit 50 them to be moved laterally relative to the work table and to the needles 7, and for this purpose the carrier member 13 is shown as pivoted to the work table at 30, and is connected by means of a suitable pivoted arm 55 31 with a vertical rock shaft 32 carrying at its lower end a cam arm 33. This cam arm 33 has a follower 34 riding in a suitable cam groove in a cam 35. This mechanism for effecting lateral movement of the button 60 clamp may be in accordance with usual practice where it is desired to oscillate the button laterally of the work table so as to bring either hole of a pair in the button into alignment with the needle path. In the present 65 instance, however, it will be noted that there

are two needles 7 which are so spaced that they may pass through two of the holes of the button simultaneously, these needles being spaced longitudinally of the machine and thus at right angles to the direction of movement of the button clamp. Each of these needles 7 has its own sewing thread, such as *a* and *b*, these threads being passed through suitable tension mechanisms as at 40 in a manner usual with two-needle sewing machines. Each of the needles, therefore, together with its cooperating instrumentalities beneath the work table, passes stitches through two holes of the button and the work, the rear needle passing stitches through the rear pair of holes of the button and the forward needle passing stitches through the forward pair of holes in the button, simultaneously, the two stitching threads lying in parallel relation on the face of the button. Thus where it is desired to set a given total number of stitches, one-half this number of needle strokes is necessary with the use of the two needles than would be required if a single needle were caused to stitch first through one set of two holes and then through the other set of two holes as in machines heretofore made.

70 In its preferred form the machine of the present invention utilizes a single looper 75 mechanism for both of the sewing needles 7. This not only simplifies the looper mechanism, but it also causes an interlocking of the two threads which effects a more secure engagement of the button to the work and permits the use of single thread chain stitches without the liability of raveling should the thread be broken at any point after the stitches have been placed. A looper mechanism capable of cooperating with the threads of both of the sewing needles is therefore illustrated in the drawings and as shown this mechanism includes a latch needle 50 similar to those commonly employed in knitting machines. Such a needle as herein shown has a hook 51 at its free end and a latch 52 freely pivoted as at 53 to the needle 50 back of the hook 51, this latch 52 being movable between a closed position where its free end 80 engages the free end of the hook, as is illustrated in Figures 3, 6, 7, 14 and 15, and an open position in which this latch extends away from the hook 51 as shown in Figures 4 and 8 to 13. As shown best in Figure 5, the rear end of the latch needle is fixed, as by a set screw 55, in a slide 56 mounted in a suitable longitudinal guideway 57 beneath the work table 1. This slide is provided with a cam follower roll, as 157, mounted on a pivot 58, this follower roll riding in a cam groove 59 in a cam 60. This cam 60 is carried by the main shaft 61 of the machine from which the reciprocations of the needle bar 5 may be produced by any usual mechanism as through a crank portion 62 of this shaft and a connect- 85 90 95 100 105 110 115 120 125 130

ing rod 63 as shown in Figure 1. Also fixed to the shaft 61 is a second cam 65 having a cam groove 66 therein in which rides a follower roll 67 rotatably carried by a block 68. 5 This block carries a plate 69 longitudinally slidably mounted on the upper face of the block 56. At the forward end of this plate 69 is pivoted as at 70, a thread finger 71 having a hooked forward extremity 72. This 10 thread finger is provided with a guide pin 74 which rides in an angular slot 73 in a stationary plate 75. The upper forward face of the slide 56 is cut away, as at 80, to permit the passage of the thread finger 71, which 15 rides on the upper face of this cut away portion.

Assuming now that a button is held by the button clamp superposed on the work in position to be fixed thereto, on the first downward 20 stroke of the needle bar 5 the sewing needles 7 pass through two of the holes of the button at one side of the central longitudinal axis of the machine as shown in Figures 2 and 8 and down through the work W. The cam 60 25 then causes the latch needle to approach the needle paths as shown in Figure 8 and when the needles 7 have reached the positions there shown, this latch needle has started on its backward stroke so that the hook 51 of the 30 needle engages the two loops of thread a' and b', the latch 52 having been opened on the forward stroke of the latch needle by engagement against the beveled edge 90 of a needle plate 92 having slots 93 at its forward end in 35 which the sewing needles 7 pass. The latch needle continues to retract, drawing the thread loops a' and b' therewith and the sewing needles 7 also retract as shown in Figure 9. As the latch needle retracts, the thread 40 finger 71 is moved forwardly, its guide pin 74 riding in the slot 73 until it passes the bend therein, whereupon the further forward motion of the thread finger causes its hooked end 72 to be swung laterally, engaging the loops 45 of thread as shown in Figure 10. The button clamp then shifts the button laterally, the work moving therewith, the cam 35 receiving its motion from the shaft 61 through suitable gearing shown at 95, so as to bring the other 50 two holes of the button into the paths of motion of the sewing needles 7 as shown in Figure 10. These sewing needles 7 then pass downwardly through these other holes in the button, as shown in Figure 11, and the latch 55 needle moves forwardly to take the thread loops a2 and b2 therefrom, which it is shown as just about to do in this figure, the thread loops a' and b' previously formed being held on the shank of the latch needle by the thread 60 finger 71 and back of the free end of the open latch 52. As the latch needle starts back with the two loops a2 and b2 in its hook, the thread finger is retracted by the action of the cam 65, freeing the thread loops a' and b', and permitting 65 them to engage the latch 52 and move it

into closed position, as indicated in Figure 6, whereupon further retraction of the latch needle causes these loops a' and b' to slip over the end of the latch needle and over the loops a2 and b2 in chain stitch formation as shown in Figure 7, the loops a2 and b2 being retained in the hook 51 in the latch needle. On the next downward stroke of the sewing needles 7 the button clamp and cloth plate have been moved to present the first pair of 70 holes in alinement therewith so that the next stitches are formed through the holes wherein the first stitches were placed and in the stitching cycle the third loops of thread are then passed about the second loops of thread a2 and b2 in the same manner that the second loops of thread a2 and b2 were passed about the first loops of thread a' and b' as previously described. It will be seen, therefore, that 75 the loops of threads formed on each sewing stroke by both of the stitching needles 7 are engaged by a single looper mechanism and the stitches completed in chain formation, the threads of both stitches being interengaged 80 and interlocked back of the button and on the back face of the work. The latch needle reciprocates once for each reciprocation of the sewing needles and is movable on one side only of the throat plate, always remaining 85 beneath it.

Figures 13 and 14 show the back face of the work after the first and second thread loops respectively have been taken, while Figure 15 shows the appearance after the 90 fourth set of loops have been taken. Figure 16 shows the general appearance of the back face of the work at the completion of the 95 sewing operation, the loops being shown somewhat loose, however, so that the position of the threads may be better followed. The 100 forward face of the button after the completion of the sewing operation shows merely two lines of stitching 100 extending across the face of the button. It will be noted that the 105 threads on the back face of the work engage over substantially the whole area bounded by the four sets of perforations through the work where the two sets of stitches have passed so that an exceedingly large area of contact between the threads and the work is produced. Moreover, it is found that the interengaging 110 and interlocking of the two sets of stitches is so secure that in case a thread breaks at any point no raveling of the thread occurs 115 so that the secureness of attachment of the button is little affected.

Moreover, this interengaging and interlocking of the two sets of threads makes unnecessary the usual knotting of the thread effected in single thread button sewing machines at the end of the sewing operation, this knotting being accomplished by passing the needle twice through the same hole in the button and which necessitates an extra stroke of the needle after the sewing stitches 120 125 130

have been completed. Thus wherever it is desired to stitch the button to the work by 24 stitches, using a single thread chain stitch machine, it is necessary to pass the needle 5 through the button holes 25 times, this requiring twenty-five revolutions of the main shaft. With the machine herein described but twelve rotations of the shaft are necessary to secure the button by the 24 stitches. Thus 10 with the same speed of rotation of the shaft, the time required to secure the button is slightly less than one-half that required in machines as heretofore constructed. While the latch needle looper mechanism herein 15 shown is particularly suitable when thread loops from a plurality of needles are to be taken together, it also has certain advantages when used with a single needle since it makes possible the use for sewing of threads of a 20 fineness or having other characteristics such as tendency to twist or snarl which cannot be used satisfactorily with rotating or oscillating loopers heretofore commonly used. The attachment of a button by stitches arranged 25 as hereinbefore described is not claimed herein but forms the subject matter of my divisional application Serial No. 614,070 for means for securing buttons to work, filed May 28, 1932.

30 While it is usually preferable to employ a single looper mechanism for both needles, both for simplicity of the machine, and also in order to effect the secure fixing of the button with a large area of engagement of the 35 threads on the work, and to avoid danger of raveling should a thread become broken, and without the necessity of a tying needle stroke, it is quite possible to so attach the button that the two threads will be quite in- 40 dependent of each other, using two latch needle looper mechanisms cooperating with the two needles. Such a construction is shown in Figures 18 to 20. As there shown the two needles are fixed to the needle bar 45 in lateral alinement with each other as shown in Figure 20 in which one needle only is shown as the other is directly behind. The looper mechanism then comprises the two latch needles 110 and 111, both carried by 50 a single looper actuating slide controlled in the same manner as the slide 56 shown in Figure 5. Between the two needles is shown positioned the guide block 115 having pointed rear ends 116 which act to open the latches 55 of both needles on their forward stroke in the same manner that the portion 90 of the block 92 acts in the machine heretofore described. Two looper fingers 120 and 121 are employed, the finger 120 cooperating with 60 the latch needle 110 and the finger 121 co-operating with the latch needle 111. These fingers are pivoted on a common pivot 122 to a slide such as shown at 69 in Figure 5 and each looper finger has a cam pin 123 riding 65 in its angular slot 124 in a fixed guide plate

The sequence of operations is identical with that heretofore described, except that each of the latch needles takes the looper thread from one of the sewing needles only and that the button clamp is moved forwardly and rearwardly instead of laterally to present each of a pair of holes in alignment with each of the stitching needles. As shown in Figure 20 this forward and rearward motion of the button clamp may be effected by means of an actuating cam 130 which acts to impart sliding motion forwardly and rearwardly to the button clamp support 131 which may be suitably guided for such movement. Where the button is sewn by such a machine the stitches lie in two groups across the outer face of the button as shown at 140 in Figure 21, but in this case lying longitudinally of the machine instead of laterally thereof as is shown in Figure 17. These sets of stitches are independent of each other throughout, lying in parallel relation back of the button as well as across its face. They are shown at 141 in Figure 22 lying in parallel relation on the back face of the work and in chain stitch formation. In Figure 23 one of the latch needles as 110 and 111 is shown as holding one of the thread loops of the chain stitch, it being noted that each of these latch needles takes but a single loop from one needle rather than two loops from both needles as in the form of machine first described.

From the foregoing description of certain machines adapted to attach buttons in accordance with this invention and the particular stitching by which this attachment is effected, it should be evident to those skilled in the art that various changes and modifications might be made without departing from the spirit or scope of this invention as defined by the appended claims.

I claim:

1. In combination, means for holding a four hole button and work in position for attaching the button to the work, and means for attaching the button to the work by two threads only, each thread passing through holes in the button, said attaching means including means for locking said threads together.
2. In combination, means for holding a four hole button and work in position for attaching the button to the work, means for attaching the button to the work by two threads only, each thread passing through a pair of holes in the button, said attaching means including means for locking said threads together on the back face of the work.
3. In combination, means for holding a four hole button and work in position for

attaching the button to the work, and means for attaching the button to the work by two threads only, one thread passing through one pair of holes in the button and the other 5 thread passing through the other pair of holes in the button, said attaching means including means for locking said threads together back of the button.

4. In combination, means for holding a 10 four hole button and work in position for attaching a button to the work, a pair of needles, means cooperating with said needles to form chain stitches, and means for relatively moving said needles and holding means to 15 cause each of said needles to pass alternately through the holes of a pair in the button and through the work and to lay the stitches in two parallel sets over the face of the button.

5. In combination, means for holding a 20 four hole button and work in position for attaching the button to the work, a pair of needles, means for relatively moving said needles and holding means to cause each of 25 said needles to pass alternately through the holes of a pair in the button and through the work, and form a loop of thread at each sewing stroke, and a single mechanism for passing both loops as formed through the 30 pair of previously formed loops in chain stitch formation.

6. In combination, a sewing needle, means for reciprocating said needle, a latch needle, means for reciprocating said latch needle once for each reciprocation of said sewing 35 needle to take thread loops from said sewing needle in one position only thereof, and a thread finger cooperating with said latch needle to cause each loop as it is taken by said latch needle to be passed through the 40 preceding loop in chain stitch formation.

7. In combination, a throat plate, a sewing needle reciprocable through said throat plate, a latch needle movable on one side only of said throat plate to take successive 45 loops of thread from said sewing needle, and a thread finger cooperating with said latch needle to cause each loop taken by said latch needle to be passed through the preceding loop in chain stitch formation.

8. In combination, a plurality of needles each arranged to form successive loops of thread, and means including a single latch needle for taking the loops as formed by all the needles and passing them through the 55 loops previously formed by said needles in chain stitch formation.

9. In combination, a pair of sewing needles movable together each to form successive loops of thread, a latch needle axially movable past the paths of said sewing needles in position to take and draw back the loops of threads therefrom as it is moved away therefrom, and means acting to hold the loops so taken as said latch needle moves to take 60 the next loops formed by said sewing needles

and to release said first mentioned loops to permit them to close the latch and to slip off from said latch needle about said next loops as said next loops are drawn back by said latch needle. 70

10. In combination, means for holding a four hole button and work in position for attaching the button to the work, a pair of sewing needles movable together through spaced holes in the button and through the work and each forming a thread loop on each pass therethrough, means for relatively moving said holding means and needles to cause needle strokes of each needle to pass through two holes of the button alternately, a latch 75 needle movable beneath the work past the paths of said sewing needles in position to take and draw back the loops of thread therefrom as it is moved away therefrom, and means acting to hold the loops so taken as 80 said latch needle is moved to take the next loops formed by said sewing needles and then to release said first mentioned loops to permit them to close the latch of said latch needle and to slip off therefrom about said 85 next formed loops as said next formed loops are drawn back by said latch needle. 90

11. In combination, means for holding a four hole button and work in position for attaching a button to the work, a pair of needles, means cooperating with each of said needles to form chain stitches, and means for relatively moving said needles, cooperating means and holding means to cause each 95 of said needles to pass alternately through a 100 pair of holes in the button and through the work and to lay the stitches in two parallel sets over the face of and back of the button.

12. In combination, means for holding a four hole button and work in position for attaching the button to the work, a pair of needles, means for relatively moving said needles and holding means to cause each of said needles to pass alternately through the 105 holes of a pair in the button and through the work and form a loop of thread at each sewing stroke, a member movable in time with said needles, and a pair of loop takers carried by said member, each cooperating with one of said needles to form stitches, to 110 secure the button to the work by two sets of 115 stitches lying in parallel relation over the face of and back of the button.

13. In combination, means for holding a four hole button and work in position for attaching the button to the work, a pair of sewing needles arranged in parallel relation and spaced substantially equal to the spacing of pairs of holes in the button, means for relatively moving said needles and holding means 120 laterally of the plane of the needles to cause each of said needles to pass alternately through the holes of a pair in the button and through the work on their sewing strokes and to form a loop of sewing thread at each 125 130

stroke, a pair of latch needles beneath the work, means for moving said latch needles transverse to the plane of said sewing needles and in time therewith, each of said latch needles taking successive loops of thread from one of said sewing needles, and elements cooperating with said latch needles to engage successively formed loops of the sewing threads in chain stitch formation.

10 14. In combination, means for holding a four hole button and work in position for attaching the button to the work, a pair of sewing needles arranged in parallel relation and spaced substantially equal to the spacing of pairs of holes in the button, a member movable laterally of the plane of the needle, a pair of latch needles carried by said member in position to take loops of thread from said sewing needles back of the work, a thread finger cooperating with each latch needle to retain thereon each thread loop taken until after the taking of a subsequent loop and then to release the retained loop to pass over the subsequent loop in chain stitch formation, and means for actuating said fingers.

15 15. In combination, means for holding a four hole button and work in position for attaching the button to the work, a pair of sewing needles arranged in parallel relation and spaced substantially equal to the spacing of pairs of holes in the button, a member movable laterally of the plane of the needles, a pair of latch needles carried by said member in position to take loops of thread from said

sewing needles back of the work, a thread finger cooperating with each latch needle to retain thereon each thread loop taken until after the taking of a subsequent loop and then to release the retained loop to pass over the subsequent loop in chain stitch formation, means for actuating said fingers, and means for opening the latches of said latch needles as they are advanced to take thread loops from said sewing needles.

20 16. In combination, means for holding a four hole button and work in position for attaching the button to the work, means for simultaneously passing a pair of threads each through a pair of holes in the button and through the work, and mechanism cooperating with said means for laying the threads in two separate groups of stitches lying in parallel relation over the face of and back of the button.

25 17. In combination, means for holding a four hole button and work in position for attaching the button to the work, means for simultaneously passing a pair of threads each through a pair of holes in the button and through the work, and mechanism cooperating with said means for laying the threads in two separate groups of stitches lying in parallel relation over the face of the button and the back face of the work.

In testimony whereof I have affixed my signature.

ROBERT L. LYONS.
